UNITED STATES PATENT OFFICE.

CHRISTOPHER ROBERT HOYME, OF NEW YORK, N. Y., ASSIGNOR TO HOWARD S. BORDEN, OF NEW YORK, N. Y.

ARTICLE OF MANUFACTURE.

Application filed February 6, 1922. Serial No. 534,557.

To all whom it may concern:

Be it known that I, CHRISTOPHER ROBERT HOYME, a citizen of the United States, residing at New York city, in the county of New York and State of New York, have invented a certain new and useful Article of Manufacture, fully described and represented in the following specification and the accompanying drawing, forming a part of

10 the same.

This invention relates to a new article of manufacture adapted to serve both as a bath towel and a sanitary bath robe.

The invention is designed to enable proprietors of hotels, bath houses, and the like, to furnish to each of their guests a sanitary bath robe. It has heretofore been customary for hotels, etc., to furnish their guests with bath towels, but it has proved commercially impossible to furnish guests with bath robes owing not only to the first cost of said garments, but more particularly to the expense which must be incurred in having the robes cleaned after use by each guest in order to maintain them in sanitary condition. By means of the present invention hotel proprietors are enabled to furnish each guest with a sanitary bath robe without increasing the expense which they have heretofore incurred in furnishing their guest with clean bath towels.

An article constructed in accordance with the invention comprises a strip of toweling of about the length of two bath towels, provided at or near its center with a head hole and having along each of its edges at opposite sides of the head hole fastenings by which the edges of opposite sides of the strip may be detachably secured together about the body when it is desired to use the article as a bath robe. When the fastenings are detached the article may be extended at full length and serves the purpose of an ordinary bath towel. Furthermore, when the fastenings are detached the article may be laundered as easily as an ordinary bath towel. While I find it desirable to construct the entire article of a single piece of toweling, it may, if desired, be formed from two pieces detachably secured together at their ends.

The accompanying drawings illustrate embodiments of the invention. In the drawings:

55 Fig. 1 is a perspective view of the new

article secured about the figure so as to form a bath robe;

Fig. 2 is a view, upon a smaller scale, of the new article spread out in condition to be used as a towel or to be laundered; and

Fig. 3 is a fragmentary view similar to Fig. 2 but showing a modification in which the new article is composed of two pieces detachably secured together.

As shown in Figs. 1 and 2 of the drawings, the new article comprises a strip 10 consisting of a single piece of toweling. As seen in the drawings, the opposite side edges of the strip 10 are straight, parallel and unhemmed. The toweling from which the strip 10 is made may be woven in a piece of the same width as the strip 10, so that the opposite side edges of the strip need not be cut, but may be, and, most desirably, are the selvage edges of the material. The strip 10 has at its center an opening 11 of such size that the head may easily be passed through it. The portion 12 of the strip 10 at one side of the opening 11 is provided along its right hand edge with fastenings 13 and along its left hand edge with fastenings 14. The portion 15 of the strip 10 at the other side of the opening 11 is provided along its right hand edge with fastenings 16, each located at the same distance from hole 11 as the fastenings 13; and adapted to be detachably secured thereto, and along its left hand edge with fastenings 17, each located at the same distance from hole 11 as the fastenings 14 and adapted to be detachably secured thereto. In order that the fastenings may not interfere with the use of the article as a towel they are most desirably all made entirely of fabric or other flexible material. In the form illustrated, each of the fastenings consists of a short piece of tape sewed to the strip 10 so that corresponding fastenings are adapted to be secured together by tying. If desired, however, one set of fastenings, for example, the fastenings 13, may consist of loops while the corresponding fastenings 16 may consist of tapes which may be passed through the loops and tied; or other types of flexible fastenings may be used.

When it is desired to use the article as a bathrobe, the opening 11 is passed over the head and the two portions 12, 15 of the strip 10 are allowed to hang down one behind the body and one in front of the body.

105

110

The fastenings 13, 14 are then secured to the fastenings 15, 16 as shown in Fig. 1.

When it is desired to use the articles as a towel the fastenings 14 and 17 and 13 and 5 16 are detached from each other so that the article may be spread out as shown in Fig. 2.

As the article may be spread out entirely flat when the fastenings are detached it may be laundered as easily as an ordinary towel.

10 In the form shown in Fig. 3, the two portions 12' and 15' of the strip are made of separate pieces of toweling, each having at one end fastenings 20, and a recess 21 between the fastenings. When the corresponding 15 fastenings 20 of the pieces 12', 15' are secured together as shown in the lower portion of Fig. 3, the recesses 21 combine to form a head opening like the opening 11 shown in Fig. 2. In the form illustrated 20 in Fig. 3, the fastenings 20 are shown as snap fastenings, but any desired form of fastenings may be used in place of those shown. It will be understood that the edges of the pieces 12', 15' of the two-part strip 25 shown in Fig. 3 are provided with fastenings such as the fastenings 13, 14, 16, 17 shown in Figs. 1 and 2.

When the modification shown in Fig. 3 is used, the fastenings 20 may be detached 30 when the article is not being worn as a bath robe so that two separate bath towels are provided.

It is apparent that the new article may be made from a woven piece of toweling without the necessity of any cutting except across 35 the ends of the strip and in forming the head hole in the form shown in Figs. 1 and 2, or the recesses in the form shown in Fig. 3. Furthermore, the amount of toweling used in the new article is the same as 40 that used in two ordinary bath towels, so by use of the invention hotel guests may be provided with bath robes as well as bath towels without any more expense, either as

to first cost, or as to laundering, than has 45 heretofore been incurred in furnishing them with bath towels.

What is claimed is:

1. An article adapted for use both as a bath towel and a bath robe, comprising a 50 strip of toweling having straight parallel side edges, being the selvage edges of the toweling throughout the length thereof and having near its middle a head opening, and co-operating fastenings located along the 55 edges of the strip upon opposite sides of the head opening and at corresponding distances therefrom.

2. An article adapted for use both as a bath towel and a bath robe, comprising a 60 relatively long and relatively narrow strip of toweling having straight parallel side edges throughout its length and having near its middle a head opening, and flexible means for detachably securing the portion of 65 each edge of the strip at one side of the head hole to the portion of each edge of the strip at the other side of the head hole.

3. An article adapted for use as a bath towel and a bath robe comprising two pieces 70 of toweling each having straight parallel side edges throughout the length thereof, said edges being the selvage edges of the toweling and each having one of its ends perpendicular to its side edges and containing a recess in 75 the middle of said end, and means located at said ends of the pieces upon each side of said recesses adapted to detachably connect the said ends together so that the two recesses form an opening which may be 80 passed over the head.

In testimony whereof I have hereunto set my hand in the presence of two subscribing witnesses.

CHRISTOPHER ROBERT HOYME.

Witnesses:

MAISIE MAURUS,
JULIUS M. LUTZ.
